CLAIM

The ornamental design for a combined charcoal igniter and handle therefor, as shown and described.

DESCRIPTION

FIG. 1 is a front elevational view of a combined charcoal igniter and handle showing my new design;

FIG. 2 is a rear elevational view thereof;

FIG. 3 is a top plan view thereof;

FIG. 4 is a bottom plan view thereof; and

FIG. 5 is a side elevational view of the handle, the opposite side being a mirror image thereof.

FIG. 1

FIG. 2
